UNITED STATES PATENT OFFICE

HERBERT H. GRUBB, OF BARABOO, WISCONSIN, ASSIGNOR TO HUMANE STANCHION WORKS, OF BARABOO, WISCONSIN, A CORPORATION OF WISCONSIN

ANIMAL STALL

Application filed February 27, 1929. Serial No. 343,077.

This invention relates to animal stalls generally used in dairy barns and more particularly to a type of stalls having stanchions secured to a frame work for holding 5 cattle in place.

A known type of construction for this purpose consists of a metal frame work having stall posts and top rails upon which a plurality of stanchions are swiveled at 10 spaced points and remote control means consisting of a lever, links and rods extending along the top rails for closing the stanchions or for permitting the same to open, the arrangement being such that all of the stanchions may be opened or closed simultaneously by manipulating a single lever from a point adjacent the end of the frame work.

In using this construction it is sometimes desirable to release cattle from some but not 20 all of the stanchions and an object of the present invention is to provide simple, convenient and reliable means for individually locking a given stanchion in closed position so that it cannot be opened by some general 25 means such as the system of links and rods referred to, although permitting this general means to be actuated to open the remainder of the stanchions.

A further object is to provide for individually latching the stanchions without interfering with the free and easy turning of the stanchions about their swivels.

Other objects and advantages reside in certain novel features of the construction, 35 arrangement and combination of parts which will be hereinafter more fully described and particularly pointed out in the appended claims, reference being had to the accompanying drawings forming a part of this specification, and in which:

Figure 1 is a view in elevation showing animal stalls embodying the present invention, two of the stall partitions 5 and portions of channel bars 4 being broken away 45 for the sake of illustration;

Figure 2 is an enlarged fragmentary perspective view of a portion of the device of Figure 1 showing the stanchion in open 50 position;

Figure 3 is a similar view showing the stanchion locked in closed position;

Figure 4 is a cross-sectional view on the line 4—4 of Figure 2;

Figure 5 is a fragmentary detail sectional view taken on the line 5—5 of Figure 3; 55 and

Figure 6 is a fragmentary view illustrating a conventional type of connection between the sure stop and the actuating rods. 60

Referring to Figure 1 of the drawings the reference numeral 1 denotes a base which may be formed of wood, concrete or other suitable material and which supports the frame work of the stalls, the base being provided with a curb 2, as is usual in such constructions. Spaced suitable distances apart and secured at their lower ends in the curb 2 are a series of stall posts 3. To the upper ends of the posts, a pair of spaced top rails 4 are secured, which are preferably in the form of channel irons as shown. Stall partitions 5 having their lower ends set in the base 1, are clamped to the posts 3 so as to separate the adjoining stalls and provide braces for the posts. Spaced between the posts and secured to the curb 2 and the top rails 4 are the stanchions. These stanchions are preferably of two-part constructions consisting of relatively stationary members 6 and movable members 7 which are pivoted together at their lower ends by hinges 8 which are secured to metal plates 9 on the curb 2 by chains 10. The members 6 and 7 may be of any suitable construction but 65 are preferably formed of channel irons lined with wood. The upper ends of the stanchion members 6 are provided with extension pieces 11 which have swivel connections 11' with supporting blocks 4' (see 70 Figure 5) secured between the top rails 4 by a bolt 25, which also secures other members to the rails as will appear hereinafter. It is to be understood that the type of 75 swivel connection 11' shown in Figure 5 is merely selected for the purpose of simplicity in illustration and that any suitable or known construction may be employed. The stanchion members 7 are somewhat longer 80 than the members 6 and extend upwardly 85

100

between the top rails 4 which serve as guiding means therefor and prevent the stanchions from turning about the swiveled pieces 11 when the stanchions are opened. 5 The rails are sufficiently spaced to readily permit the stanchions to turn when they are closed, however.

For moving the members 7 along the rails to provide for the opening and closing of the stanchions, remote control means is provided. 10 This means consists of a pair of rods 12 mounted in suitable journal brackets on the top rails 4, U-shaped members or clevises 13 mounted at spaced points along the rods 12 by coupling members 14, and means for reciprocating the rods. Each clevis is designed to engage the upper end of a stanchion member 7 as shown in Figure 2, so that when the rods are moved to the right 15 the stanchion will be closed and when moved to the left the stanchion will be opened due to the action of gravity upon the member 7. As shown in Figure 1, the means for reciprocating the rods 12 consists of a link 15 and a hand lever 16, the link being secured to the rods at one end and pivoted upon the lever 16 at the other end. The lever is pivoted at the point 17 to the top rails 4.

For providing means for insuring the closing of all of the stanchions when the rods are actuated, the upper end of each stanchion member 7 is provided with a metal plate 18 which carries a projection 19 which provides a cam surface. If a clevis 13 has been raised and the rods moved to the right the stanchion can not be closed by movement of the rods unless some means is provided for causing the clevis to ride over the upper end of the member 7. In the present construction, the provision of the cam surface 19 causes the clevises 13 to ride over the upper end of the member 7 when the rods 12 are moved to the left so that when the rods are again moved to the right 45 all of the stanchions will be closed.

For preventing cattle from taking the wrong place when the stanchions are opened, the stalls are provided with rods 20 and 21, commonly called "sure-stops" which are 50 adapted to be actuated by movement of the rods 12 (see Figure 6) to project into the spaces between the stanchions and the posts when the stanchions are opened. The lower ends of the rods 20 are pivoted to the posts 55 as shown while the upper ends are loosely connected to the rods 12. A system of links 22 connects the rods 20 and 21 and causes movement of the rod 21 when the rod 20 is moved. With this construction it will be 60 seen that the "sure-stops" are folded up and out of the way when the stanchions are closed.

As shown particularly in Figures 2, 3 and 4, means is provided for individually 65 locking each stanchion in closed position so

that it is not operated by the remote control means. In accordance with the construction shown, this locking means consists of two metallic plates 24 and 28 which are secured on opposite sides of the top rails 70 4 by means of the bolt 25 and which are curved around the lower flange of the top rail to provide hook portions 26 and 30 disposed at right angles to each other. A bolt 27 is provided with an eye which receives 75 the hook 30 of the plate 28. When the plate 28 is clamped in position, as shown in Figure 4, the bolt 27 is pivotally mounted on the top rails. When the bolt 27 is moved so that its free end engages the hook 26, the 80 stanchion is locked in closed position since the member 7 cannot be moved along the top rails. The individual lock, thus provided, is normally not used, the movable member 7 of the stanchion being held in closed position by the clevis 13 and the rods 12 as explained above. If, however, it is desired to lock one of the stanchions in closed position while permitting the remainder to be opened, the bolt 27 is placed in the hook 26 85 after the stanchion is closed so that the parts take the position shown in Figure 3. The remainder of the stanchions may then be opened to release cattle therein by operating the lever 16 to move the rods 12, but 90 the stanchion held closed by the bolt 27 will not be opened. Because of the spacing of the bolt 27 with respect to the movable member 7 the lock does not interfere with the free swiveling movement of the stanchion 100 as a whole about the chain 10 and the swivel connection on the member 11.

While only one embodiment of the invention has been shown and described herein it is obvious that many changes may be made 105 in the construction and arrangement of the parts without departing from the spirit of the invention or the scope of the annexed claims.

What I claim is:

1. In an animal stall arrangement having a framework, stanchions, adapted to be opened and closed, secured thereto and means for controlling the opening and closing of the stanchions from a remote point, a locking device for maintaining one of the stanchions in closed position independent of said means, said device consisting of a hook secured to the framework at a point adjacent said stanchion and a bolt pivotally mounted on the framework and adapted to engage said hook. 115

2. In an animal stall arrangement including a framework having stall partitions and top rails, stanchions mounted on the framework and so arranged that the upper end of one member of each stanchion is adapted to be moved along the top rails to open and close the stanchions and means for controlling movement of the members from a remote 120 125 130 point.

point, a locking device for maintaining one of the stanchions in closed position independent of said means, said device consisting of a hook secured to said top rails at a point adjacent a movable stanchion member and a bolt pivotally mounted on said top rails and adapted to engage said hook to limit movement of said movable stanchion member along said top rails.

3. In combination, an animal stall having a framework, a stanchion adapted to be opened and closed mounted thereon, means for controlling the opening and closing of the stanchion from a remote point and a locking device for maintaining said stanchion in closed position independent of said means, said device consisting of a hook secured to the framework at a point adjacent the stanchion and a bolt pivotally mounted on a framework and adapted to engage said hook.

4. In combination, an animal stall having stall posts and a pair of top rails, a stanchion having one member thereof disposed between the top rails and adapted to move along the same to open and close the stanchion, means for controlling the position of said stanchion member from a remote point and a device for limiting movement of said member to maintain the stanchion in closed position, said device including a bolt pivotally mounted to one of said top rails and means for holding said bolt transversely of the rails.

35 In witness whereof, I hereto affix my signature.

HERBERT H. GRUBB.
